JAMES W. PASSMAN, OF NEWARK, OHIO, ASSIGNOR TO PAKO CORPORATION, OF MINNEAPOLIS, MINNESOTA, A CORPORATION OF DELAWARE.

PHOTOGLAZING METHOD AND APPARATUS.

Application filed December 5, 1923. Serial No. 678,697.

This invention relates to a method and apparatus for glazing photographic or similar prints. In previous methods of glazing prints it has been common to use ferro-typing apparatus usually comprising a smooth or polished plate of iron covered with a thin coat of japan enamel, together with squeegeeing apparatus. The plate was carefully washed and then coated with a thin film of some glazing or ferro-typing liquid, among which the following were used, namely, paraffin wax dissolved in benzine, certain commercial automobile polishes and a solution of castile soap. The wet photographic print was then laid face down on the plate and pressed tightly thereon with a heavy pressure by a squeegee roller or machine. The print was then allowed to dry. In some cases, the print would come off the plate readily when dried, but in most cases it was necessary to peel the print off with a flat-edged instrument. Recently, it has been the occasional practice to heat the plate to hasten the drying of the print.

It is an object of this invention to provide a method of glazing prints which may be performed with an apparatus comprising a revoluble member preferably of cylindrical form which is coated with a certain lubricant or glazing solution, against which revoluble member the print, which is also coated with said solution, is held and progressed by a comparatively soft apron, preferably of absorbent fabric material.

It is a further object of the invention to provide such an apparatus comprising a revoluble member, together with means for continuously coating the same with the glazing solution and an endless fabric apron which contacts and moves with the cylinder for a considerable portion of its periphery and which holds the print against the cylinder with the emulsion side of the print in contact with the cylinder, means being provided for heating the cylinder.

It is a further object of the invention to provide such a revoluble member or cylinder having a polished surface and which cylinder, preferably, comprises a copper base coated with nickel.

It is still another object of the invention to provide means for progressively bringing the print into contact with the smooth or polished surface of said revoluble member, which means preferably comprises a roller

in contact with the apron which travels against the cylinder, which roller presses the apron against the cylinder.

It is also an object of the invention to provide means adjacent said above mentioned roller for preventing contact of the print with the revoluble member or cylinder until the same has passed beneath said roller.

It is still a further object of the invention to provide such an apparatus comprising a continuously moving revoluble cylinder and endless apron moving thereagainst together with the means for lubricating the surface of said cylinder, which means, preferably, comprises a sheet of absorbent material of sufficient extent and sufficiently weighted to effectively coat said surface of the cylinder.

These and other objects and advantages of the invention will be fully set forth in the following description made in connection with the accompanying drawings in which like reference characters refer to the same parts throughout the different views, and in which—

Fig. 1 is a view in end elevation of the apparatus, a small portion being broken away and showing a vertical section; and

Fig. 2 is a plan view of the apparatus, certain parts being broken away.

Referring to the drawings, the device comprises a frame having end portions composed of vertical members 1 and 2 connected by the horizontal top member 3, the intermediate horizontal member 4 and the lower horizontal member 5. A rail, preferably formed of a rod or tubing 6 is secured to the top of the cross member 3 and projects vertically therefrom in substantially rectangular form. It will be understood that there are two end frames and the same are connected by suitable longitudinally extending headed and nutted bolts 7 which pass through the members of the end frame and also, in practice, pass through the pipe sections extending between and abutting the inside of the end frame members. Secured beneath the members 3 substantially midway between the vertical members 1 and 2, are bearings 8 secured in place by suitable headed and nutted bolts and said bearings have journaled therein an axle member 9 carrying a spider bracket 10 adjacent each end which is attached by suitable bolts or rivets to a revoluble member 11, which, in the embodiment of the invention illustrated, is shown

110

as a cylinder. While the axle member 9 could be made of various forms, in the embodiment of the invention illustrated, the same is shown as being made hollow and as being closed at one end and provided inside of the member 11 with a plurality of holes 9^a so that the said member 9 constitutes a gas conduit and burner adapted to heat the member 11 and the surface thereof. The member 11, preferably, is of copper or provided with a copper base and the peripheral surface thereof is coated with nickel and polished. The member 11 is formed with solid end walls which, however, are pierced by a plurality of holes 11^a adapted to furnish air to the gas burner and form a convenient means for lighting the same. The bearings 8 may, if desired, carry ball bearing housings or other anti-friction bearings which, will form the bearings for the member 9. A member 12 is provided which comprises a sheet of comparatively soft and absorbent material such as fabric and this sheet is adapted to travel in contact with the peripheral surface of the member 11 for a considerable portion of said surface. While various materials may be used for the member 12, in practice it has been found that the commercial product known as "diaper cloth" forms a good efficient material. In the embodiment of the invention illustrated the member 12 is shown as an endless belt or apron supported upon various revoluble rollers. Two of these rollers are shown as 13 and 14 carried on shafts journaled in the front projecting portion of member 3. From the roller 14 the member 12 passes downwardly toward the surface of member 11 and runs over a roller 15 carried on a shaft journaled in a pair of arms 16, which arms are pivoted adjacent their lower ends in shafts or bolts 17 extending through the vertical member 1. The roller 15 normally is held in position against the apron 12 and the surface of member 11. From the roller 15, the member 12 extends around the surface of member 11 in close contact therewith to a point adjacent a roller 18 carried on a shaft journaled in the vertical members 2 adjacent the top thereof. The member 12 then passes outside of roller 18 and downwardly to and around rollers 19 carried on spaced shafts journaled in the members 5. From the roller 19 the belt 12 passes upwardly and forwardly to the roller 13. A tightening roller 20 is adapted to contact the inside of the apron 12 beneath the projecting portion of member 3, which roller is carried on a shaft journaled in a pair of arms 21, projecting forwardly from the outer side of the vertical members 1 and supported on the pivot which supports the arms 16. The apron 12 is driven by the roller 18 and said roller is turned by a pulley 22 secured to its shaft and which is driven by a belt 23 pass-

ing over the driving pulley 24 of a suitable motor 25 illustrated as supported on the member 5. A bar 26 shown as a flat slat, extends between the members 3 adjacent the surface of member 11 and slightly above the roller 15.

In the print-glazing process using the present apparatus, the surface of member 11 is moistened or coated with a suitable glazing or ferro-typing solution and means are provided for applying this solution to the surface of member 11. While various forms of such means could be used, in the embodiment of the invention illustrated, the same is shown as comprising a piece or pad of absorbent fabric material 27. While various materials might be used, in practice it has been found that a good grade of flannel makes a very efficient material. The pad or flap 27 is secured at its upper end to a rod 28 supported at its ends in arms 29 at each end of the cylinder 11, which arms are pivoted by suitable pivot bolts in the members 3. The arms 29 are connected by tension springs 30 to the upper ends of arms 16 so that when the member 27 is in position shown in Fig. 1, said springs will be under tension and will move the arms 16 toward the cylinder 11 and press the roller 15 thereagainst. The pad 27 has secured thereto a plurality of spaced slats or bars 31 which are connected adjacent their ends by flexible members 32 which are also secured to the rod 28. While various forms of flexible members might be used, in the embodiment of the invention illustrated, the same are shown as small chains which have been found very suitable in practice. The vertical members 2, at their rear sides, carry brackets 33 adapted to support a removable box or tray 34, the top of which is disposed adjacent the roller 18.

In carrying out the novel print-glazing method in connection with the apparatus described, the motor 25 is driven and, in turn, drives the roller 18, which moves the apron 12 in the direction indicated by the arrows. The apron 12, by its contact with the cylinder 11 turns the same, the cylinder being freely revoluble. The gas burner 9-9^a will be lighted and the flap or pad 27 will be saturated with the glazing or ferro-typing solution used. It will be noted that pad 27 can be lifted from the cylinder 11 by swinging the arms 29 forwardly. When this is done, the tension of spring 30 will be relaxed and arms 16 will move forwardly, thus relieving the pressure of roller 15 from the surface of cylinder 11. The belt tighter 20-21 which will be of considerable weight, will tend to tighten the apron 11 and will also assist in moving the roller 15 away from cylinder 11, the pad 27 being supplied with the glazing or ferro-typing solution which will herein be referred to as

the lubricant. The cylinder will be revolved until the said lubricant is suitably applied thereto. The photographic prints in wet saturated condition will be dipped in a solution of the lubricant and placed on the apron 12 between the rollers 13 and 14 with the emulsion side upward. As the apron 12 moves inward, the cylinder 11 and prints will be carried therewith and will pass over the roller 15. As the print is thus gripped or pinched between the roller 15 and apron 12 and the surface of the cylinder 11, the same will be progressively pressed against the surface of cylinder 11 with its emulsion side contacting said surface. As the prints are thus drawn between the apron 12 and the surface of member 11, the rear edge of the print sometimes has a tendency to flip over against the member 11. Such action would be objectionable as the print must be brought progressively in contact with the surface of cylinder 11 so that it will lie perfectly flat against said surface and contact the same at all points. To prevent this flipping action and premature contact of the print the bar 26 is provided and will insure that the print cannot contact the cylinder 11 until it passes the roller 15. The apron 12 moves the cylinder 11 and travels with the surface thereof so that the print is held against the surface of cylinder 11 from the roller 15 and until the roller 18 is substantially reached. While the print is thus being carried about the cylinder 11, the same is heated and the emulsion and the glazing lubricant are baked, dried and hardened. By the time most of the prints reach the roller 18, the process is completed and the prints, after passing the roller 18, snap off of the cylinder 12 and drop into the tray 34. A few of the prints will travel slightly past the roller 18 in contact with the cylinder 11, but before traveling far, will also snap off of the cylinder and drop into the tray 34. It is unnecessary, therefore, to remove the prints from the cylinder 11. As stated, the same snap off of the cylinder with a cracking or popping noise much like that made by popcorn popping. The surface of member 11 continues to move past roller 18 and is again lubricated by the member 27 and prepared for other prints so that the process is continuous. The member 12, preferably, is made of absorbent material so as to absorb some of the moisture from the print and the apron is substantially dry when it again passes the rollers 13 and 14 and in condition to receive more prints. As one of the trays 34 becomes filled with prints, it may be removed and another tray placed in position.

From the above description it is seen that applicant has provided a simple and efficient process and apparatus for glazing photographic and similar prints. The apparatus has been amply demonstrated in actual prac-

tice for a considerable period and found to be very successful with various kinds of photographic papers. The inventor made numerous tests with the member 11 made of different materials and it has been found, by actual experiment that the nickel plated copper cylinder gives results far superior to any other known material. The exact reason of this is not altogether known, but one factor at least is thought to be that the copper is a very dense and compact material and when coated with nickel a very smooth, dense compact surface is obtained with which the emulsion on the prints advantageously co-operates. There may also be some relation between the specific material used and the glazing or ferro-typing solution, although just what this action is is not at present understood. The fact is, however, that the results obtained are very satisfactory and an unusually high grade of glazed print is produced. The previous squeegeeing and other pressing operations always performed in the ferro-typing process involving a heavy pressure are eliminated and the necessary removal of the prints from the ferro-typing surface is also eliminated. As stated, the prints pop and snap from the cylinder in perfect condition. The cylinder retains its polish and it is unnecessary to continuously polish the cylinder as it has been necessary to always clean and polish between each use the ferro-typing plates or members heretofore used. As above stated, the process and apparatus have been in actual commercial use for some time and have given uniform and unusually high grade results.

It will, of course, be understood that various changes may be made in the nature and sequence of the various steps of the process and in the form, details, arrangement and proportions of the parts of the apparatus without departing from the scope of applicant's invention, which, generally stated, consists in a device capable of carrying out the objects above stated, such as shown and described and defined in the appended claims.

What is claimed is:

1. A print-glazing apparatus having in combination, a revoluble rigid member having a smooth polished peripheral surface and a flexible member adapted to contact and travel with said surface for a portion of its revolution and carry a photographic print with the emulsion side thereof against said surface, said print being carried between said revoluble member and said flexible member.

2. A print-glazing apparatus comprising a revoluble cylinder having a smooth polished peripheral surface and a movable apron of comparatively soft flexible material contacting an appreciable portion of said sur-

- face and adapted to move therewith and carry a print around said cylinder with its emulsion side in contact with said peripheral surface of the cylinder.
5. 3. A print-glazing apparatus having in combination, a revolute rigid member having a polished peripheral surface, means for heating said member and surface, and means moving with said surface for pressing a 10 photoprint pressed flat against said surface with its emulsion side contacting the same and progressing said print with said surface for a portion of its revolution.
15. 4. A print-glazing apparatus having in combination, a revolute rigid member having a polished peripheral surface, means for heating said member and surface, and means for pressing a photoprint flat against said surface with its emulsion side contacting the 20 same and progressing said print with said surface for a portion of its revolution, and means supplying a film of ferro-typing solution to said surface.
25. 5. In a print-glazing apparatus, a revolute rigid cylinder having a smooth periphery, means for supplying a lubricant to said periphery and an endless belt of comparatively soft absorbent material contacting said cylinder for a portion of its periphery, moving therewith and adapted to hold a photographic print with its emulsion side against said periphery.
35. 6. In a print-glazing apparatus, a revolute rigid cylinder having a smooth peripheral surface, a flexible endless apron of comparatively soft material traveling partially around said cylinder and moving therewith for a portion of its revolution, and a sheet of absorbent material contacting 40 said cylinder in advance of said apron adapted to apply a film of ferro-typing solution thereto.
45. 7. A print-glazing apparatus having in combination, a rigid revolute member having a polished peripheral surface, means for heating said member and surface, a flexible apron of comparatively soft absorbent material contacting said peripheral surface and moving therewith for a portion of 50 its revolution, and a revolute member contacting said apron and pressing the same against said member at the side of said member which said apron approaches, said last mentioned revolute member adapted to 55 progressively press a photographic print against said first mentioned revolute member, which print is carried between said flexible apron and said polished peripheral surface of said first mentioned revolute 60 member with its emulsion side in contact with said surface.
65. 8. The structure set forth in claim 7, and means extending across said first mentioned revolute member adjacent the surface thereof above said last mentioned revolute
- member to prevent a print contacting said surface before passing said last mentioned revolute member.
9. A print-glazing apparatus having in combination, a frame, a rigid cylinder revolutely mounted therein having a smooth peripheral surface, an endless apron of comparatively soft and absorbent fabric material contacting a material portion of said surface and moving in contact therewith, a roller pressing said apron against said cylinder, and a sheet of absorbent material contacting said surface of said cylinder in advance of said roller for applying a film of ferro-typing solution thereto. 70
10. In a print-glazing machine, a rigid member having a smooth polished peripheral surface movable in a curved path, means for holding a photoprint against said surface and moving with said surface and photoprint with the emulsion side of said print against said surface, and means for heating said print while against said surface. 75
11. In a print-glazing machine, a rigid revolute member having a polished surface, said member comprising a copper base plated with nickel. 80
12. A print-glazing machine having in combination, a continuously moving rigid smooth surface, means for continuously applying a film of lubricant to said surface, continuously moving means for pressing a photoprint against said surface with its emulsion side contacting said surface, and means for heating said surface to bake, dry and harden said print. 85
13. A print-glazing machine having in combination, a frame, a rigid cylinder revolutely mounted therein having a smooth peripheral surface, an endless apron traveling about rollers having axes substantially parallel to the axis of said cylinder, said apron contacting said cylinder for a material portion of its periphery and extending forwardly from said cylinder in a substantially horizontal plane, a frame extending transversely of said cylinder in advance of the horizontal portion of said apron and carrying a sheet of absorbent fabric material adapted to rest upon and conform to the shape of said peripheral surface and adapted to apply a film of ferro-typing solution thereto. 90
14. In a print-glazing machine, a nickel plated copper member having a polished surface movable in a curved path, and means for holding a photoprint against said surface, and moving the same therewith. 95
15. The process of glazing photographic or similar prints which comprises lubricating a continuously moving smooth rigid surface, pressing the print against said lubricated surface with its emulsion side contacting said surface, moving said prints 100
- 110
- 115
- 120
- 125
- 130

- with said surface while pressed thereagainst, and heating said surface to bake, dry and harden said prints.
16. The process of glazing photographic or similar prints which consists in lubricating a smooth polished surface of a revoluble rigid cylinder, pressing said prints against said surface with their emulsion sides thereagainst, by means of a relatively soft absorbent member, progressing said prints and member with said surface and simultaneously heating said prints to bake, dry and harden the same.
17. The process of glazing photographic or similar prints which consists in pressing the prints against the moving smooth surface of a nickel-plated copper member with the emulsion side of the prints against said surface, by means of a relatively soft absorbent sheet of material, progressing said surface and sheet with the prints thereagainst and simultaneously heating said surface to bake, dry and harden said prints.
18. The process of glazing photographic or similar prints comprising dipping the wet prints in a glazing solution, applying a film of ferro-typing solution to a rigid smooth moving surface, pressing said prints against said surface with their emulsion sides in contact therewith and advancing said prints with said surface and holding the same thereagainst with a comparatively soft absorbent backing member, and simultaneously heating said surface and prints to dry, bake and harden said prints.
19. The process of glazing a photographic or similar print comprising, dipping the washed and wet print in a glazing lubricant, applying a film of ferro-typing liquid to the smooth surface of a moving rigid member, bringing the emulsion side of said print progressively into contact with said surface, holding said print pressed against said surface and moving the same therewith and simultaneously heating said surface and print to dry, bake and harden said print.
20. The process of glazing photographic or similar prints which consists in immersing said prints in a glazing solution, then pressing the prints against the smooth surface of a nickel-plated copper member and holding the same thereagainst and heating said member and surface.
21. The process of glazing photographic or similar prints which consists in wetting the smooth surface of a nickel-plated copper member with a glazing or ferro-typing solution, pressing a photographic print thereagainst with its emulsion side contacting said surface holding said print against said surface and heating said surface to dry, bake and harden said print.
22. The process of glazing photographic prints which consists in immersing the wet prints in a glazing solution, then pressing said prints against the heated smooth peripheral surface of a rigid moving member with their emulsion side contacting said surface.
23. A print-glazing apparatus comprising a nickel-plated copper member having a smooth polished surface.
24. In a print-glazing machine, a member having a continuously moving rigid smooth polished surface and means movable in contact with said surface for pressing a photoprint against said surface with its emulsion side contacting said surface and means for heating said surface to bake, dry and harden said print.
25. In a print-glazing machine, a member having a continuously moving rigid smooth polished surface, a yielding means, movable with said surface for pressing a photoprint against said surface with its emulsion side contacting said surface, and means for heating said surface to bake, dry and harden said print.
26. A print glazing apparatus comprising a rigid member having a smooth polished surface, means for pressing a photographic print against said surface with its emulsion side contacting the same, and means adjacent said means for preventing contact of said print with said surface before pressed thereagainst by said first mentioned means.
27. A print glazing apparatus comprising a rigid member having a smooth polished surface, a rotatable member for pressing a photographic print against said surface with its emulsion side contacting the same, and means for preventing contact of said print with said surface before being pressed thereagainst by said rotatable member.
28. A print glazing apparatus comprising a rigid revoluble member having a smooth peripheral surface, a revoluble member arranged to progressively press a photographic print against said surface, and means for preventing premature contact of said print with said surface.
29. A print glazing apparatus having in combination, a revoluble rigid member having a smooth polished periphery, a movable fabric member adapted to contact said periphery and press a photographic print against the same with the emulsion side of said print engaging said member.
30. A print glazing apparatus having in combination, a rigid movable member having a smooth polished surface, means for applying a film of ferro-typing solution to said surface, means for pressing a photoprint against said surface with its emulsion side engaging said surface, and means for applying heat to said member while in motion with said print thereon.
31. The process of glazing photographic prints which consists in progressing a smooth polished surface of a movable member, moist-

- tening said surface with a ferro-typing solution, placing a wet photographic print on said surface with its emulsion side contacting said surface, pressing said print against said surface during the progression thereof, and heating said surface to dry, bake, harden and glaze said print. 5
32. A print glazing apparatus having in combination, a moving member having a smooth polished surface, means for applying a ferro-typing solution to said surface, means for pressing a photographic print against said surface, and means for heating said member and surface. 10
33. The process of glazing photographic prints which consists in immersing the prints in a glazing solution, placing said prints on the smooth polished surface of a moving member with its emulsion side contacting said surface, pressing said prints against said surface, moving said member and surface with the prints thereon and applying heat to said member to bake, dry, harden and glaze said prints. 15
34. The process of glazing photographic prints which consists in applying a film of glazing or ferrotyping solution to the smooth polished moving surface of a movable member, placing a wet photoprint on said surface with its emulsion side contacting said surface, pressing said print against said surface and applying heat to said member while moving to dry, bake, harden and glaze said print. 20
35. The process of glazing photographic prints which consists in immersing the prints in a glazing solution, supporting the prints on a smooth polished metal surface of a member with its emulsion side contacting said surface, pressing said prints against said surface and progressing said surface and member, and simultaneously applying heat thereto to bake, dry, harden and glaze said prints. 25
36. A print glazing apparatus having in combination, a moving member having a smooth polished surface, means for applying a lubricant to said surface, and means for holding a photographic print with its emulsion side against said surface. 30
37. A print glazing apparatus having in combination, a moving member having a smooth polished surface, means for applying a lubricant to said surface, means for pressing a photographic print with its emulsion side against said surface, and means for heating said surface. 35
38. A print glazing apparatus having in combination, a movable member having a rigid smooth surface movable with said member in a curved path, means for applying a film of ferro-typing liquid to said surface, and means for pressing a photoprint against said surface with its emulsion side contacting said surface. 40
39. A print glazing apparatus having in combination, a movable member having a rigid smooth surface movable with said member, means for applying a ferro-typing liquid to said surface, and an endless member for holding a photoprint against said surface with its emulsion side contacting said surface. 45
40. A print-glazing apparatus comprising a movable nickelplated metal member having a surface movable therewith, means for applying a lubricant to said surface, and means for pressing a photo-print against said surface with its emulsion side contacting said surface. 50
41. A print-glazing apparatus comprising a movable nickel-plated metal member having a surface movable therewith, and means for holding a photo-print with its whole emulsion face flat against said surface. 55
42. A print-glazing apparatus having in combination, a moving member having smooth surface and a movable fabric member adapted to contact said surface and press a photographic print against the same with the emulsion side of said print engaging said surface. 60
43. The process of glazing photographic or similar prints which consists in lubricating a smooth polished surface of a revolute rigid cylinder, pressing said prints against said surface with their emulsion sides thereagainst, by means of a relatively soft absorbent member, and progressing said prints and member with said surface to dry and harden the same. 65

In testimony whereof I affix my signature.

JAMES W. PASSMAN.
